(57) **ABSTRACT**

An article bender apparatus that assists in joining two separate malleable article line free ends in a selected helical wrap, the article bender apparatus including a disc that has a slot disposed therethrough that originates from the center at a root extending radially outward, a shoe having a selectable pivotal lock to a face of the disc, wherein the shoe is in an open state when the slot is open and the shoe is in a closed locked state when the shoe partially covers the slot leaving the slot root section open. Also, a means for rotating the disc about the root, operationally the disc is inserted onto a first line free end portion to the root, the shoe is placed in the closed locked state, with the shoe intersecting a second line free end portion, next rotating the disc to helically wrap the second line about the first line.

ARTICLE BENDER APPARATUS

RELATED PATENT APPLICATION

This application claims the benefit of U.S. provisional patent application Ser. No. 63/286,103 filed on Dec. 6, 2021 by Joshua Cosby of Falfurrias, Texas, U.S.

TECHNICAL FIELD

The present invention relates generally to an article bender apparatus, which is employed to assist in joining two separate malleable article line free ends via bending and wrapping the article free ends together. More particularly, the present invention of the article bender apparatus manually joins a first line free end portion and a second line free end portion that are at substantially right angles to one another, wherein the second article free end portion is selectively helically wrapped about the first line free end portion.

BACKGROUND OF INVENTION

It is frequently needed on farms and ranches to manually install or repair fences, wherein it is required to join pre-made fencing sections that come rolled and when unrolled each end needs to be joined, which can actually be simply done with pliers, however, to increase the ease and speed of joining the first and second line free ends, a dedicated tool is better that can accommodate different size lines (diameter wise), help make the mechanical advantage better for easier wire bending via multiple handle positioning, ratchets, and the like.

Thus, the prior art recognizes these issues with various apparatus and devices that assist the individual in tying fence wire ends together. Looking at the prior art in this area in U.S. Pat. No. 3,297,060 to Richardson, disclosed is a wire splicer that includes a ratchet type head assembly with a handle, and within the head assembly is a disc with a slot that captures a first wire with the disc having an axial extension having a slot that captures a second wire. In Richardson, in looking at FIG. 4 it looks as though the second wire must be positioned at an angle to the first wire, as opposed to the standard practice of the first and second wire being at about right angles to one another.

Continuing in the prior art for wire tying tools, in U.S. Pat. No. 1,861,308 to Goldenstar, disclosed is a wire tying tool that also has a ratchet head assembly having a disc with a slot, with a handle extending from the head assembly, wherein a jaw (29) projects from the head assembly axially to encompass the second wire at more or less at a right angle to the first wire, it is not apparent that the wire size is adjustable or that the first wire is secured within the disc.

Further, in the prior art for wire twisters and splicers, in U.S. Pat. No. 756,148 to Simpson, disclosed is a wire twister/splicer that includes again a ratchet head and handle extending therefrom, wherein the ratchet head has slot to receive the first wire, with the head having an encapsulated slot extending axially to hold the second wire, with a pivoting cover to hold the second wire in the slot that does allow the second wire to be at a right angle to the first wire, but not accommodating different wire sizes or helical wrap axial clearance.

Next, a wire splicer is disclosed in U.S. Pat. No. 2,153,079 to Featherston, that as in the prior examples in the prior art, has a ratchet head with a handle extending therefrom with a fixed slot in the head for the first wire with a pivoting

shoe portion that encompasses the second wire, however, it looks as though the shoe would not provide adequate clearance for succeeding axial helical wraps, see FIG. 6, again it does not look like different wire sizes are accommodated easily either.

Moving onward, in the wire splicer arts in U.S. Pat. No. 1,129,711 to Mumford, disclosed is a ratchet head with a handle extending therefrom with a slot in the head for the first wire with a slotted barrel to accommodate the second wire, however, it looks as though the barrel shape would not provide adequate axial clearance for succeeding helical wraps, plus the slotted barrel looks oversize to accommodate larger second wires, but this would make it difficult to helically wrap smaller second wires axially adjacent to one another.

Next, a wire splicer is disclosed in U.S. Pat. No. 374,650 to Batters, that is a simple one-piece device with essentially a hook at the end of a handle that requires a clamping wrench to hold the first wire and second wire parallel to one another prior to winding.

Continuing, a wire splicer is disclosed in U.S. Pat. No. 868,178 to Goughnour, that is similar to Featherston and Mumford, as Goughnour plus as in the prior examples in the prior art has a ratchet head with a handle extending therefrom with a slot in the head for the first wire with a slotted barrel to accommodate the second wire, however, it looks as though the slotted barrel would not provide adequate clearance for succeeding axial helical wraps, again it does not look like different wire sizes are accommodated easily.

Further, a wire splicer is disclosed in U.S. Pat. No. 1,754,023 to Jones, that discloses a wire splicer that includes a pivot squeeze handle for encompassing the first wire, wherein the handle is used in a swing around manner to make the helical wrap of the second wire about the first wire, wherein a lug (30) with grooves accommodates the second wire for bending about the first wire, again it does not look like different wire sizes are accommodated easily.

What is needed is an article bender apparatus that has several improvements over the prior art that include the ability to accommodate different wire sizes with precision for axially winding the helical wrap with a professional appearance, also a second wire guide shoe that provides an operational clearance both axially and radially for subsequent helical wraps to make professional helical wraps of the second wire about the first wire in a sequential manner.

SUMMARY OF INVENTION

An article bender apparatus that assists in joining two separate malleable article line free ends that are defined as a first line free end portion with a first line long axis and a second line free end portion with a second line long axis when the first and second line long axes are positioned substantially perpendicular to one another, the article bender apparatus assists in joining the first and second line free end portions in a selected helical wrap. The article bender apparatus including a disc having a first face portion and an opposing second face portion, further the disc having an outer periphery portion that is about a longitudinal axis that is centered in the disc, wherein the longitudinal axis is positioned perpendicular to both the first and second face portions, in addition the disc has a slot disposed therethrough from the first face portion to the second face portion, wherein the slot originates from the longitudinal axis in a root section then extending in a radial fashion to the outer periphery portion of the disc.

Further included in the article bender apparatus is a shoe that is planar in shape having a primary planar face portion and an opposing secondary planar face portion, the shoe has a lengthwise axis and a perpendicularly positioned shortwise axis, the shoe also has a first end portion and an opposing second end portion with the lengthwise axis spanning therebetween, further the shoe has an axial axis that is perpendicular to both the lengthwise and shortwise axes, wherein the axial axis spans between the primary and secondary planar face portions, also the axial axis is positioned parallel to the disc longitudinal axis with the primary planar face portion having a slidable engagement to the disc first face portion, the shoe first end portion terminates in a first channel that is positioned longwise to be parallel to the shortwise axis.

Additionally included in the article bender apparatus is a means for a selectable pivotal lock with pivotal movement between the disc and the shoe, the pivotal lock is about the axial axis, wherein the shoe is an open operational state when the slot is fully open and the shoe is in a closed locked operational state when the shoe partially covers the slot leaving the slot root section open.

Also included in the article bender apparatus is a means for imparting a rotational movement to the disc, wherein the rotational movement is about the longitudinal axis, wherein operationally the disc is inserted onto the first line free end portion with the first line long axis therethrough the disc slot from the outer periphery portion to the root section resulting in the longitudinal axis and the first line long axis being substantially co-incident to one another, next the shoe is manually moved through the pivotal movement from the open state to the closed locked state resulting in the first line free end portion being secured within the root section. Continuing simultaneously during the shoe being manually moved, the first channel is aligned to partially encompass the second line free end portion, resulting in both the first line free end portion being secured within the root section and the shoe first channel to partially encompass the second line free end portion, next the imparting of rotational movement to the disc is initiated to result in the selected helical wrap of the second line free end portion around the first line free end portion being about the first line long axis.

These and other objects of the present invention will become more readily appreciated and understood from a consideration of the following detailed description of the exemplary embodiments of the present invention when taken together with the accompanying drawings, in which;

BRIEF DESCRIPTION OF DRAWINGS

FIG. 1 shows a side elevation view of the article bender apparatus that includes the receptacle, the cover ring, the receptacle handle, the disc, wherein the disc slot and the receptacle slot are aligned, and the cam lock clamp with the quick release handle is shown on the disc in the locked or closed operational state with the quick release handle being adjacent to the disc first face portion;

FIG. 2 shows a close-up side elevation view of the article bender apparatus that includes the receptacle, the cover ring, a portion of the receptacle handle, the disc, wherein the disc slot and the receptacle slot are not aligned, and the cam lock clamp with the quick release handle is shown on the disc in the locked or closed operational state with the quick release handle being adjacent to the disc first face portion;

FIG. 3 shows an expanded front perspective view of the article bender apparatus that includes the receptacle, the cover ring, a portion of the receptacle handle, the disc,

wherein the disc slot and the receptacle slot are aligned, and the cam lock clamp with the quick release handle is shown on the disc in the locked or closed operational state with the quick release handle being adjacent to the disc first face portion;

FIG. 4 shows a close-up side elevation view of the article bender apparatus that is an opposite or opposing side view of FIG. 2, wherein FIG. 4 includes the receptacle, noting that the cover ring is not shown in this view as it is on the opposite side and shown in FIG. 4 is the solid opposing side of the receptacle, further shown is a portion of the receptacle handle, the disc, wherein the disc slot and the receptacle slot are aligned, and the cam lock clamp with the quick release handle is not shown as being on the opposite side of the disc, as FIG. 4 also shows the shoe and the angularly displaced retainer bar both mounted on the axial pivot bolt, plus the stop pin for the retainer bar, note for pictorial clarity, the flat spring and pivot rod are not shown;

FIG. 5 shows a side elevation view of the disc with the slot and slot root section, wherein also shown is the shoe and the angularly displaced retainer bar that are both pivotally attached by the axial pivot bolt, further shown in FIG. 5 is the retainer bar stop pin, the flat spring with the pivot rod and the pivot rod aperture, in addition to the flat spring handle;

FIG. 6 shows an opposing side elevation view of FIG. 5, wherein FIG. 6 shows the disc with the slot and slot root section, wherein also shown is the cam lock clamp with the quick release handle being shown on the disc in the locked or closed operational state with the quick release handle being adjacent to the disc first face portion, also shown is the flat spring handle with the pivot rod and the pivot rod aperture, plus the handle ball protrusion and the receiving depression for the handle ball protrusion that through pivot rod pivotal movement secures the pivot rod in a locked position for the flat spring (not shown);

FIG. 7 shows the side elevation view of FIG. 6, however, with the flat spring handle moved into the locked position, wherein FIG. 7 shows the disc with the slot and slot root section, wherein also shown is the cam lock clamp with the quick release handle being shown on the disc in the locked or closed operational state with the quick release handle being adjacent to the disc first face portion, also shown is the flat spring handle with the pivot rod and the pivot rod aperture, plus the handle ball protrusion and the receiving depression connected for locking the flat spring handle that through pivot rod pivotal movement secures the pivot rod in a locked position for the flat spring (not shown);

FIG. 8 is a front perspective view of FIG. 5, wherein FIG. 8 shows the disc with the slot and slot root section, wherein also shown is the shoe and the angularly displaced retainer bar that are both pivotally attached by the axial pivot bolt, further shown in FIG. 8 is the retainer bar stop pin, the flat spring with the pivot rod and the pivot rod aperture;

FIG. 9 shows the side elevation view of FIG. 5, wherein FIG. 9 shows the flat spring pivoted through pivotal movement being moved downward away from the disc slot and disc slot root section, wherein also shown is the shoe and the angularly displaced retainer bar that are both pivotally attached by the axial pivot bolt, with the shoe and retainer bar pivotally moved past the slot root section, further shown in FIG. 9 is the retainer bar stop pin, and the flat spring with the pivot rod and the pivot rod aperture;

FIG. 10 shows the side elevation view of FIG. 5, wherein FIG. 10 shows a lower perspective view of the disc with the slot and slot root section, wherein also shown is the shoe and the angularly displaced retainer bar that are both pivotally attached by the axial pivot bolt, further shown in FIG. 10 is

the retainer bar stop pin, the flat spring with the pivot rod and the pivot rod aperture, in addition to the flat spring handle;

FIG. 11 shows a top view of the shoe and the angled retainer bar including the shoe first ridge and the shoe first channel, and the shoe aperture;

FIG. 12 shows a bottom view of the shoe and the angled retainer bar including the shoe aperture;

FIG. 13 shows an end view of the shoe and the retainer bar including the shoe first ridge and the shoe first channel with the axial axis;

FIG. 14 shows a top elevation view of the shoe and the retainer bar including the first ridge and the first channel with the axial axis;

FIG. 15 is view 15-15 from FIG. 13, wherein FIG. 15 shows the first channel and first ridge with their associated chamfers being chamfers 480, 485 disposed on the first ridge and chamfer 490 disposed on the first channel;

FIG. 16 shows a side elevation cutaway view of the receptacle with partial handle, with the receptacle having the cover ring removed to expose the disc with the outer periphery portion having the asymmetrical gear teeth wherein the disc outer periphery and asymmetrical gear teeth are slidably engaged with the slide surface and the radial internal diameter plus the internal diameter to have the disc retained within the receptacle while allowing free clockwise rotation about the longitudinal axis, also shown in FIG. 16 is the pawl asymmetrical gear teeth engaged to the disc outer periphery and asymmetrical gear teeth thus forming the first operational state of the ratchet, further shown is the means for means for biasing the pawl toward the arcuate convergence, wherein receptacle handle movement clockwise about the longitudinal axis will move the disc in rotational lockstep in the clockwise rotation about the longitudinal axis, further ratchet handle rotation counterclockwise about the longitudinal axis through the ratchet will allow the disc to either be static rotationally or freely rotate clockwise about the longitudinal axis;

FIG. 17 shows the side elevation view of FIG. 16, except wherein FIG. 17 shows the ratchet in the second operational state with the pawl asymmetrical gear teeth disengaged to the disc outer periphery and asymmetrical gear teeth thus allowing free rotation of the receptacle handle counterclockwise about the longitudinal axis and the disc free rotation clockwise about the longitudinal axis, wherein the pawl is moved away from the arcuate convergence against the means for biasing the pawl by the aforementioned relative asymmetrical gear teeth movement of the pawl and disc, further FIG. 17 shows the side elevation cutaway view of the receptacle with partial handle, with the receptacle having the cover ring removed to expose the disc with the outer periphery portion having the asymmetrical gear teeth wherein the disc outer periphery and asymmetrical gear teeth are slidably disengaged, with the slide surface and the radial internal diameter plus the internal diameter to have the disc retained within the receptacle;

FIG. 18 shows the side elevation view of FIG. 16, wherein in FIG. 18 the disc slot is rotated about the longitudinal axis to show the disc slot (with no gear teeth) suspended over the pawl asymmetrical gear teeth, further the side elevation cutaway view of the receptacle with partial handle, with the receptacle having the cover ring removed to expose the disc with the outer periphery portion having the asymmetrical gear teeth wherein the disc outer periphery and asymmetrical gear teeth are slidably engaged with the slide surface and the radial internal diameter plus the internal diameter to have the disc retained within the receptacle while allowing free clockwise rotation about the longitudinal axis, also shown in

FIG. 18 is the pawl asymmetrical gear teeth engaged to the disc outer periphery and asymmetrical gear teeth thus forming the first operational state of the ratchet, further shown is the means for means for biasing the pawl toward the arcuate convergence, additionally the constant operational gap is shown along with the converging operational gap as between the pawl primary and secondary margins and the recessed cavity of the receptacle first and second boundary arc margins, wherein receptacle handle movement clockwise about the longitudinal axis will move the disc in rotational lockstep in the clockwise rotation about the longitudinal axis, further receptacle handle rotation counterclockwise about the longitudinal axis through the ratchet will allow the disc to either be static rotationally or freely rotate clockwise about the longitudinal axis;

FIG. 19 shows a close-up of the asymmetrical gear teeth of either the disc outer periphery portion or the pawl to define the tooth height distance;

FIG. 20 is view 20-20 from FIG. 18, wherein FIG. 20 shows detail of the receptacle, cover ring, and disc outer periphery asymmetric gear teeth slidable interface along with the internal diameter of the receptacle, slide surface of the receptacle, the top surface of the receptacle, and internal diameter of the cover ring;

FIG. 21 shows a bottom perspective view of the core of the ratchet with the disc shown with the outer periphery and symmetrical gear teeth disposed on the disc outer periphery and the pawl with the asymmetrical gear teeth, further with the pawl second side, the pawl primary boundary margin, and the pawl secondary boundary margin;

FIG. 22 shows an upper perspective view of the article bender apparatus in use with the initial use step shown of the disc slot being positioned adjacent to a first line with the shoe and the retainer bar in the open state along with the flat spring pivoted away from the disc slot, noting that the second line is positioned substantially perpendicular to the first line, note that for pictorial clarity the ratchet, receptacle, and receptacle handle are not shown;

FIG. 23 shows an upper perspective view of the article bender apparatus in use with the second use step shown of the disc slot root section being positioned adjacent to the first line with the shoe and the retainer bar in the closed operational state with the retainer bar contacting the first line in the disc slot root section along with the flat spring pivoted away from the disc slot, noting that the second line is positioned substantially perpendicular to the first line and that the shoe can now be placed into the closed operational state, note that for pictorial clarity the ratchet, receptacle, and receptacle handle are not shown;

FIG. 24 shows a disc side elevation view and a shoe and retainer bar end view of FIG. 23, wherein FIG. 24 shows the first line in the root section of the slot of the disc retained by the retainer bar with the shoe and the retainer bar in the closed operational state that helps position the first channel to the second line free end portion, further shown is the shoe first channel partially encompassing the second line and being held in place by the flat spring applying pressure onto the second line into the first channel of the shoe, wherein with the manual rotation of the disc the shoe first channel will wrap the second line helically about the first line, note that for pictorial clarity the ratchet, receptacle, and receptacle handle are not shown;

FIG. 25 shows a lower perspective view of FIG. 24, wherein FIG. 25 shows a disc bottom view and a shoe and retainer bar bottom view of FIG. 24, wherein FIG. 25 shows the first line in the root section of the slot of the disc contacted by the retainer bar with the shoe and the retainer

bar in the closed operational state, further shown is the shoe first channel partially encompassing the second line and being held in place by the flat spring applying pressure onto the second line into the first channel of the shoe, wherein with the manual rotation of the disc the shoe first channel will wrap the second line helically about the first line, note that for pictorial clarity the ratchet, receptacle, and receptacle handle are not shown;

FIG. 26 shows an upper perspective view of the article bender apparatus in a third use step of starting to engage in rotational movement of the disc thus starting the selected helical wrap of the second line about the first line, note that for pictorial clarity the ratchet, receptacle, and receptacle handle are not shown;

FIG. 27 shows an upper perspective view of the article bender apparatus in a fourth use step of continuing to engage in rotational movement of the disc thus continuing the selected helical wrap of the second line about the first line, note that for pictorial clarity the ratchet, receptacle, and receptacle handle are not shown;

FIG. 28 shows an upper perspective view of the article bender apparatus in a fifth use step of further continuing to engage in rotational movement of the disc thus further continuing the selected helical wrap of the second line about the first line, note that for pictorial clarity the ratchet, receptacle, and receptacle handle are not shown;

FIG. 29 shows an upper perspective view of the article bender apparatus in a sixth use step of further continuing to engage in rotational movement of the disc thus further continuing the selected helical wrap of the second line about the first line resulting in multiple helical wraps of the second line about the first line, note that for pictorial clarity the ratchet, receptacle, and receptacle handle are not shown; and

FIG. 30 shows an upper perspective view of the article bender apparatus in a final use step of the second line terminating therethrough the first channel of the shoe and retainer bar thus ending the selected helical wrap of the second line about the first line, wherein the shoe and retainer bar is moved from the closed operational state to the open operational state of the cam lock clamp with quick release handle resulting in axial looseness of the pivot bolt to enable the first line to be removed from the disc slot root section, with the flat spring (not shown) in the same state as shown in FIG. 22, this in FIG. 30 shown is removing the article bender apparatus from the first line, note that for pictorial clarity the ratchet, receptacle, and receptacle handle are not shown.

- 376 Short side of the clockwise asymmetrical gear teeth 375 (or termed saw tooth or serrated teeth) interface of the disc 90 outer periphery portion 105
- 377 Long side of the clockwise asymmetrical gear teeth 375 (or termed saw tooth or serrated teeth) interface of the disc 90 outer periphery portion 105
- 385 Clockwise rotational direction of the disc 90
- 386 Pawl 360 and spring 391 recessed cavity
- 387 Floor or slide surface of the recessed cavity 386
- 388 First arc boundary margin consistent radius portion from longitudinal axis 110
- 389 Second arc boundary margin decreasing radius portion defined as radius two 393 from longitudinal axis 110 forming an arcuate convergence as between the pawl 360 and the second arc boundary margin 389 as radius four 395 and radius two 393 converge toward one another thus decreasing gap 397 such that eventually the second arc boundary margin 389 and the radius four 395 come into contact with one another tightly wedging the pawl 360 between the second arc boundary margin 389 and the disc 90 outer periphery 105 clockwise asymmetrical gear teeth 375 of the receptacle 356 to lock the ratchet 355 to transmit clockwise

- rotation 385 to the disc 90 from the handle 345 and receptacle 356 about the longitudinal axis 110
- 390 Counterclockwise rotational direction of the disc 90
- 391 Means for biasing the pawl 360 toward the arcuate convergence 389 wherein the means 391 is preferably a spring
- 392 First radius or radius 1 one of the receptacle 356 that is consistent in distance from the longitudinal axis 110 that forms part of the recessed cavity 386 defined as the slide surface 387 termination margin
- 393 Second radius or radius 2 two of the receptacle 356 that is decreasing in distance from the longitudinal axis 110 that forms part of recessed cavity 386 defined as the slide surface 387 converging termination margin
- 394 Third radius or radius 3 three of the pawl 360 that is consistent in distance from the longitudinal axis 110 defined as the pawl 360 primary boundary margin
- 395 Fourth radius or radius 4 four of the pawl 360 that is decreasing in distance from the longitudinal axis 110 defined as the pawl 360 secondary boundary margin
- 396 Consistent operational gap width as between the radius three 394 and the radius one 392, wherein the operational gap 396 is disposed within the cavity 386
- 397 Converging operational gap width as between the radius four 395 and the radius two 393, wherein the operational gap 397 is shown as reducing in gap size as in converging, being disposed within the cavity 386
- 398 Tooth height of the short side 376 of the clockwise asymmetrical gear teeth 361, 375 (or termed saw tooth or serrated teeth) interface of the disc 90 outer periphery portion 105 or pawl 360 and the long side 377 of the clockwise asymmetrical gear teeth 361, 375 (or termed saw tooth or serrated teeth) interface of the disc 90 outer periphery portion 105 or pawl 350
- 400 First operational state of the ratchet 355 with the clockwise pawl 360 teeth 361 engaged to the disc 90 outer periphery portion 105 saw tooth clockwise tooth interface 375 that rotationally only allows clockwise disc rotation 385 in rotational lockstep with the receptacle 356, with the pawl 360 teeth 361 disengaged from the saw tooth interface 375 on the disc 90 outer periphery portion 105, the disc 90 can only rotate clockwise 385 independently from the receptacle 356
- 401 Pawl 360 movement to engage into the clockwise asymmetrical gear teeth 375 (or termed saw tooth or serrated teeth) interface of the disc 90 outer periphery portion 105 and the pawl 360 asymmetrical gear teeth 361 form the locking of the ratchet 355 to transmit clockwise rotation 385 to the disc 90 from the handle 345 and receptacle 356 about the longitudinal axis 110
- 402 Pawl 360 movement to disengage the clockwise asymmetrical gear teeth 375 (or termed saw tooth or serrated teeth) interface of the disc 90 outer periphery portion 105 and the pawl 360 asymmetrical gear teeth 361 form the unlocking of the ratchet 355 to allow free clockwise rotation 385 of the disc 90 within the receptacle 356 about the longitudinal axis 110
- 403 Primary boundary margin in a constant arc being radius three 394 of the pawl 360
- 404 Secondary boundary margin in a decreasing arc being radius four 395 of the pawl
- 405 Second operational state of the ratchet 355 with the pawl 360 teeth 361 disengaged to the disc 90 outer periphery 105 saw tooth counterclockwise tooth interface 375 that rotationally allows counterclockwise receptacle 356 movement 351 or complementary clockwise disc 90 rotation 385 with the pawl 360 teeth

11

- 361 disengaged from the disc 90 outer periphery portion 105 saw tooth interface 375
- 406 Means 391 extension of the pawl 360
- 415 Finger hole aperture in the disc 90 for manually rotating the disc 90 about the longitudinal axis 110 in clockwise rotation 385 of the disc 90 for alignment and positioning of the disc 90 slot 120, receptacle 356 slot 367, and the first line free end portion 55, note that counter clockwise rotation 390 of the disc 90 is prevented by the ratchet and pawl mechanism 355
- 420 Cam lock clamp with a quick release handle that pulls a pivot bolt 425 when the handle
- 421 Locked or closed operational state of the cam lock clamp 420 wherein the pivot bolt 425 is pulled axially tight forming a clamp similar to a common bicycle axle cam lock clamp, positionally the cam lock 420 handle is adjacent to the disc 90 first face portion 95 in the locked state 421
- 422 Open or released operational state of the cam lock clamp 420 wherein the pivot bolt 425 is released to be loose axially to open the clamp that is in closed state 421, wherein the cam lock 420 handle is moved away from to the disc 90 first face portion 95 to extend perpendicular to the to the disc 90 first face portion 95 in the released state 422
- 425 Axle axial pivot bolt of the cam lock clamp 420 that is about the axial axis 180 disposed therethrough said disc 90, retainer bar 450, and shoe 135 utilizing aperture shoe aperture 181
- 430 Flat spring with an arcuate shape
- 435 Pivot rod of the flat spring 430
- 440 Handle for the flat spring 430 and pivot rod 435
- 445 Flat spring aperture for the pivot rod 435 disposed within the disc 90
- 450 Retainer bar for the root section 125 of the slot 120
- 455 Stop pin for the retainer bar 450 pivotal movement that is about the axle axial pivot bolt 425, wherein the stop pin 455 is disposed within the disc 90, stop pin 455 is for the retainer bar 450 to stop only by virtue of a height limitation of the pin 455 extending from the disc 90 second face portion 100 with the stop pin 455 height only contacting the retainer bar 450, wherein the stop pin 455 is not high enough to contact the shoe 135
- 460 Pivotal movement manually of the flat spring 430 about the pivot rod 435 using the handle 440
- 465 Spring ball protrusion for the handle 440 for the purpose of locking the movement 460 of the flat spring 430 via the handle 440 into the disc 90 first face portion 95
- 466 Radius of the first channel 200 of the shoe 135
- 470 Receiving depression for the ball protrusion 465, wherein the receiving depression is disposed in the disc 90 first face portion 95
- 475 Acute angle between the lengthwise axis 155 and the first ridge 205
- 480 Chamfer radius disposed at the acute angle 475 on the first ridge 205
- 485 Chamfer radius disposed at the acute angle 210 on the first ridge 205 of the shoe 135
- 490 Chamfer radius at the first channel 200 of the shoe 135 approximately equal to the channel radius 466
- 491 Sidewall of the first channel 200
- 495 Channel 200 sidewall 491 chamfer that is approximately equal to one-half of the radius 466
- 500 Relief notch positioned at the trailing edge of the channel 220 that is operational to loosen the helical wrap 85 about the first line free end portion 55 for help

12

5 with wire stress on the second line free end portion 65 and for help of the ease of manually creating the helical wrap 85 on the second line free end portion 65 by the user

DETAILED DESCRIPTION

With initial reference to FIG. 1 shows a side elevation view of the article bender apparatus 50 that includes the receptacle 356, the cover ring 371, the receptacle 356 handle 345, the disc 90, wherein the disc 90 slot 120 and the receptacle 356 slot 367 are aligned, and the cam lock clamp 420 with the quick release handle is shown on the disc 90 in the locked or closed operational state 421 with the quick release handle being adjacent to the disc 90 first face portion 95.

Continuing, FIG. 2 shows a close-up side elevation view of the article bender apparatus 50 that includes the receptacle 356, the cover ring 371, a portion of the receptacle 356 handle 345, the disc 90, wherein the disc 90 slot 120 and the receptacle 356 slot 367 are not aligned, and the cam lock clamp 420 with the quick release handle is shown on the disc 90 in the locked or closed operational state 421 with the quick release handle being adjacent to the disc 90 first face portion 95.

Next, FIG. 3 shows an expanded front perspective view of the article bender apparatus 50 that includes the receptacle 356, the cover ring 371, a portion of the receptacle 356 handle 345, the disc 90, wherein the disc 90 slot 120 and the receptacle 356 slot 367 are aligned, and the cam lock clamp 420 with the quick release handle is shown on the disc in the locked or closed operational state 421 with the quick release handle being adjacent to the disc 90 first face portion 95.

Further, FIG. 4 shows a close-up side elevation view of the article bender apparatus 50 that is an opposite or opposing side view of FIG. 2, wherein FIG. 4 includes the receptacle 356, noting that the cover ring 371 is not shown in this view as it is on the opposite side and shown in FIG. 4 is the solid opposing side of the receptacle 356, further shown is a portion of the receptacle 356 handle 345, the disc 90, wherein the disc 90 slot 120 and the receptacle 356 slot 367 are aligned, and the cam lock clamp 420 with the quick release handle is not shown as being on the opposite side of the disc 90, as FIG. 4 also shows the shoe 135 and the angularly displaced retainer bar 450 both mounted on the axial pivot bolt 425, plus the stop pin 455 for the retainer bar 450, note for pictorial clarity, the flat spring 430 and pivot rod 435 are not shown.

50 Moving onward, FIG. 5 shows a side elevation view of the disc 90 with the slot 120 and slot root section 125, wherein also shown is the shoe 135 and the angularly displaced retainer bar 450 that are both pivotally attached by the axial pivot bolt 425, further shown in FIG. 5 is the retainer bar 450

55 stop pin 455, the flat spring 430 with the pivot rod 435 and the pivot rod aperture 445, in addition to the flat spring handle 440.

Further, FIG. 6 shows an opposing side elevation view of FIG. 5, wherein FIG. 6 shows the disc 90 with the slot 120 and slot root section 125, wherein also shown is the cam lock clamp 420 with the quick release handle being shown on the disc 90 in the locked or closed operational state 421 with the quick release handle being adjacent to the disc 90 first face portion 95, also shown is the flat spring 430 handle 440 with the pivot rod 435 and the pivot rod 435 aperture 445, plus the handle 440 ball protrusion 465 and the receiving depression 470 for the handle 440 ball protrusion 465 that through

pivot rod 435 pivotal movement 460 secures the pivot rod 435 in a locked position for the flat spring 430 (not shown).

Next, FIG. 7 shows the side elevation view of FIG. 6, however, with the flat spring 430 handle 440 moved into the locked position, wherein FIG. 7 shows the disc 90 with the slot 120 and slot root section 125, wherein also shown is the cam lock clamp 420 with the quick release handle being shown on the disc 90 in the locked or closed operational state 421 with the quick release handle being adjacent to the disc 90 first face portion 95, also shown is the flat spring 430 handle 440 with the pivot rod 435 and the pivot rod 435 aperture 445, plus the handle 440 ball protrusion 465 and the receiving depression 470 connected for locking the flat spring 430 handle 440 that through pivot rod 435 pivotal movement 460 secures the pivot rod 435 in a locked position for the flat spring 430 (not shown).

Moving on, FIG. 8 is a front perspective view of FIG. 5, wherein FIG. 8 shows the disc 90 with the slot 120 and slot root section 125, wherein also shown is the shoe 135 and the angularly displaced retainer bar 450 that are both pivotally attached by the axial pivot bolt 425, further shown in FIG. 8 is the retainer bar 450 stop pin 455, the flat spring 430 with the pivot rod 435 and the pivot rod aperture 445.

Next, FIG. 9 shows the side elevation view of FIG. 5, wherein FIG. 9 shows the flat spring 430 pivoted through pivotal movement 460 being moved downward away from the disc 90 slot 120 and disc slot root section 125, wherein also shown is the shoe 135 and the angularly displaced retainer bar 450 that are both pivotally attached by the axial pivot bolt 425, with the shoe 135 and retainer bar 450 pivotally moved past the slot 120 root section 125, further shown in FIG. 9 is the retainer bar 450 stop pin 455, and the flat spring 430 with the pivot rod 435 and the pivot rod aperture 445.

Continuing, FIG. 10 shows the side elevation view of FIG. 5, wherein FIG. 10 shows a lower perspective view of the disc 90 with the slot 120 and slot root section 125, wherein also shown is the shoe 135 and the angularly displaced retainer bar 450 that are both pivotally attached by the axial pivot bolt 425, further shown in FIG. 10 is the retainer bar 450 stop pin 455, the flat spring 430 with the pivot rod 435 and the pivot rod aperture 445, in addition to the flat spring handle 440.

Further, FIG. 11 shows a top view of the shoe 135 and the angled retainer bar 450 including the shoe 135 first ridge 205 and the shoe first channel 200, and the shoe 135 aperture 181. Next, FIG. 12 shows a bottom view of the shoe 135 and the angled retainer bar 450 including the shoe 135 aperture 181. Further, FIG. 13 shows an end view of the shoe 135 and the retainer bar 450 including the shoe 135 first ridge 205 and the shoe 135 first channel 200 with the axial axis 180. Continuing, FIG. 14 shows a top elevation view of the shoe 135 and the retainer bar 450 including the first ridge 205 and the first channel 200 with the axial axis 180. Next, FIG. 15 is view 15-15 from FIG. 13, wherein FIG. 15 shows the first channel 200 and first ridge 205 with their associated chamfers being chamfers 480, 485 disposed on the first ridge 205 and chamfer 490 disposed on the first channel 200.

Moving onward, FIG. 16 shows a side elevation cutaway view of the receptacle 356 with partial handle 345, with the receptacle 356 having the cover ring 371 removed to expose the disc 90 with the outer periphery portion 105 having the asymmetrical gear teeth 375 wherein the disc 90 outer periphery 105 and asymmetrical gear teeth 375 are slidably engaged with the slide surface 357 and the radial internal diameter 358 plus the internal diameter 366 to have the disc 90 retained within the receptacle 356 while allowing free

clockwise rotation 385 about the longitudinal axis 110, also shown in FIG. 16 is the pawl 360 asymmetrical gear teeth 361 engaged to the disc 90 outer periphery 105 and asymmetrical gear teeth 375 thus forming the first operational state 400 of the ratchet 355. Further shown in FIG. 16 is the means for means 391 for biasing the pawl 360 toward the arcuate convergence 389, wherein receptacle 356 handle 345 movement clockwise 350 about the longitudinal axis 110 will move the disc 90 in rotational lockstep in a clockwise rotation 350, 385 about the longitudinal axis 110, further ratchet 355 handle 345 rotation counterclockwise 351 about the longitudinal axis 110 through the ratchet 355 will allow the disc 90 to either be static rotationally or freely rotate clockwise 385 about the longitudinal axis 110.

Further, FIG. 17 shows the side elevation view of FIG. 16, except wherein FIG. 17 shows the ratchet 355 in the second operational state 405 with the pawl 360 asymmetrical gear teeth 361 disengaged to the disc 90 outer periphery 105 and asymmetrical gear teeth 375 thus allowing free rotation 351 of the receptacle 356 handle 345 counterclockwise 351 about the longitudinal axis 110 and the disc 90 free rotation clockwise 385 about the longitudinal axis 110, wherein the pawl 360 is moved away from the arcuate convergence 389 against the means 391 for biasing the pawl 360 by the aforementioned relative asymmetrical gear teeth 361, 375 movement of the pawl 360 and disc 90. Further FIG. 17 shows the side elevation cutaway view of the receptacle 356 with partial handle 345, with the receptacle 356 having the cover ring 371 removed to expose the disc 90 with the outer periphery portion 105 having the asymmetrical gear teeth 375, wherein the disc 90 outer periphery 105 and asymmetrical gear teeth 375 are slidably disengaged 405, with the slide surface 357 and the radial internal diameter 358 plus the internal diameter 366 to have the disc 90 retained within the receptacle 356.

Continuing, FIG. 18 shows the side elevation view of FIG. 16, wherein FIG. 18 the disc 90 slot 120 is rotated 385 about the longitudinal axis 110 to show the disc 90 slot 120 (with no gear teeth) suspended over the pawl 360 asymmetrical gear teeth 361, further the side elevation cutaway view of the receptacle 356 with partial handle 345, with the receptacle 356 having the cover ring 371 removed to expose the disc 90 with the outer periphery portion 105 having the asymmetrical gear teeth 375 wherein the disc 90 outer periphery 105 and asymmetrical gear teeth 375 are slidably engaged with the slide surface 357 and the radial internal diameter 358 plus the internal diameter 366 to have the disc 90 retained within the receptacle 356 while allowing free clockwise rotation 385 about the longitudinal axis 110. Also shown in FIG. 18 is the pawl 360 asymmetrical gear teeth 361 engaged to the disc 90 outer periphery 105 and asymmetrical gear teeth 375 thus forming the first operational state 400 of the ratchet 355, further shown is the means for means 391 for biasing the pawl 360 toward the arcuate convergence 389.

Additionally FIG. 18 shows the constant operational gap 396 is shown along with the converging operational gap 397 as between the pawl 360 primary 403 and secondary 404 margins and the recessed cavity 386 of the receptacle 356 first 388 and second 389 boundary arc margins, wherein receptacle 356 handle movement 345 clockwise 350 about the longitudinal axis 110 will move the disc 90 in rotational lockstep in the clockwise rotation 385 about the longitudinal axis 110, further receptacle 356 handle 345 rotation counterclockwise 351 about the longitudinal axis 110 through the

15

ratchet 355 will allow the disc 90 to either be static rotationally or freely rotate clockwise 385 about the longitudinal axis 110.

Further, FIG. 19 shows a close-up of the asymmetrical gear teeth 361, 375 of either the disc 90 outer periphery portion 105 or the pawl 360 to define the tooth height 398 distance. Next, FIG. 20 is view 20-20 from FIG. 18, wherein FIG. 20 shows detail of the receptacle 356, cover ring 371, and disc 90 outer periphery 105 asymmetric gear teeth 375 slidable interface 357 along with the internal diameter 366 of the receptacle 356, slide surface 357 of the receptacle 356, the top surface 359 of the receptacle 356, and internal diameter 366 of the cover ring 371. Further, FIG. 21 shows a bottom perspective view of the core of the ratchet 355 with the disc 90 shown with the outer periphery 105 and symmetrical gear teeth 375 disposed on the disc 90 outer periphery 105 and the pawl 360 with the asymmetrical gear teeth 361, further with the pawl 360 second side 365, the pawl 360 primary boundary margin 403, and the pawl 360 secondary boundary margin 404.

Next, FIG. 22 shows an upper perspective view of the article bender apparatus 50 in use with the initial use step shown of the disc 90 slot 120 being positioned adjacent to the first line 55 with the shoe 135 and the retainer bar 450 in the open state 250, 422 along with the flat spring 430 pivoted away 460 from the disc 90 slot 120, noting that the second line 65 is positioned substantially perpendicular 75 to the first line 55, note that for pictorial clarity the ratchet 355, receptacle 356, and receptacle 356 handle 345 are not shown.

Further, FIG. 23 shows an upper perspective view of the article bender apparatus 50 in use with the second use step shown of the disc 90 slot 120 root section 125 being positioned adjacent to the first line 55 with the shoe 135 and the retainer bar 450 in the closed operational state 255, 421 with the retainer bar 450 contacting the first line 55 in the disc 90 slot 120 root section 125 along with the flat spring 430 pivoted away from the disc 90 slot 120, noting that the second line 65 is positioned substantially perpendicular 75 to the first line 55 and that the shoe 135 can now be placed into the closed operational state 255, 421, note that for pictorial clarity the ratchet 355, receptacle 356, and receptacle 356 handle 345 are not shown.

Continuing, FIG. 24 shows a disc 90 side elevation view and the shoe 135 and retainer bar 450 end view of FIG. 23, wherein FIG. 24 shows the first line 55 in the root section 125 of the slot 120 of the disc 90 contacting the retainer bar 450 with the shoe 135 and the retainer bar 450 in the closed operational state 255, 421 that positions the first channel 200 in relation to the second line free end portion 65 as the shoe 135 first channel 200 partially is encompassing the second line 65 and being held in place by the flat spring 430 applying pressure onto the second line 65 into the first channel 200 of the shoe 135, wherein with the manual rotation 350, 385 of the disc 90 the shoe 135 first channel 200 will wrap 85 the second line 65 helically about the first line 55, note that for pictorial clarity the ratchet 355, receptacle 356, and receptacle 356 handle 345 are not shown.

Moving onward, FIG. 25 shows a lower perspective view of FIG. 24, wherein FIG. 25 shows the disc 90 bottom view and the shoe 135 and retainer bar 450 bottom view of FIG. 24, wherein FIG. 25 shows the first line 55 in the root section 125 of the slot 120 of the disc 90 contacted by the retainer bar 450 with the shoe 135 and the retainer bar 450 in the closed operational state 255, 421. Further shown in FIG. 25 is the shoe 135 first channel 200 partially encompassing the

16

second line 65 and being held in place by the flat spring 430 applying pressure onto the second line 65 into the first channel 200 of the shoe 135, wherein with the manual rotation 385 of the disc 90 the shoe 135 first channel 200 will wrap 85 the second line 65 helically 85 about the first line 55, note that for pictorial clarity the ratchet 355, receptacle 356, and receptacle 356 handle 345 are not shown.

Next, FIG. 26 shows an upper perspective view of the article bender apparatus 50 in a third use step of starting to engage in rotational movement 385 of the disc 90 thus starting the selected helical wrap 85 of the second line 65 about the first line 55, note that for pictorial clarity the ratchet 355, receptacle 356, and receptacle 356 handle 345 are not shown.

Further, FIG. 27 shows an upper perspective view of the article bender apparatus 50 in a fourth use step of continuing to engage in rotational movement 385 of the disc 90 thus continuing the selected helical wrap 85 of the second line 65 about the first line 55, note that for pictorial clarity the ratchet 355, receptacle 356, and receptacle 356 handle 345 are not shown.

In addition, FIG. 28 shows an upper perspective view of the article bender apparatus 50 in a fifth use step of further continuing to engage in rotational movement 385 of the disc 90 thus further continuing the selected helical wrap 85 of the second line 65 about the first line 55, note that for pictorial clarity the ratchet 355, receptacle 356, and receptacle 356 handle 345 are not shown.

Next, FIG. 29 shows an upper perspective view of the article bender apparatus 50 in a sixth use step of further continuing to engage in rotational movement 385 of the disc 90 thus further continuing the selected helical wrap 85 of the second line 65 about the first line 55 resulting in multiple helical wraps 85 of the second line 65 about the first line 55, note that for pictorial clarity the ratchet 355, receptacle 356, and receptacle 356 handle 345 are not shown.

Further, FIG. 30 shows an upper perspective view of the article bender apparatus 50 in a final use step of the second line 65 terminating therethrough the first channel 200 of the shoe 135 and retainer bar 450 thus ending the selected helical wrap 85 of the second line 65 about the first line 55. Wherein in FIG. 30 the shoe 135 and retainer bar 450 is moved from the closed operational state 255, 421 to the open operational state 250, 422 of the cam lock clamp 420 with quick release handle resulting in axial looseness 422 of the pivot bolt 425 to enable the first line 55 to be removed from the disc 90 slot 120 root section 125, with the flat spring 430 (not shown) in the same state as shown in FIG. 22. Thus, in FIG. 30 shown is removing of the article bender apparatus 50 from the first line 55, note that for pictorial clarity the ratchet 355, receptacle 356, and receptacle 356 handle 345 are not shown.

Broadly in referring to FIGS. 1 to 30 the article bender apparatus 50 is disclosed that assists in joining two separate malleable article line free ends that are defined as a first line free end portion 55 with a first line long axis 60 and a second line free end portion 65 with a second line long axis 70 when the first 60 and second 70 line long axes are positioned substantially perpendicular 75 to one another, the article bender apparatus 50 assists in joining 80 the first 55 and second line 65 free end portions in a selected helical wrap 85, see FIGS. 22 to 30. The article bender apparatus 50 including the disc 90 having a first face portion 95 and an opposing second face portion 100, further the disc 90 having an outer periphery portion 105 that is about a longitudinal axis 110 that is centered in the disc 90, wherein the longitudinal axis 110 is positioned perpendicular 115 to both the

first 95 and second 100 face portions. In addition, the disc 90 has a slot 120 disposed therethrough from the first face portion 95 to the second face portion 100, wherein the slot 120 originates from the longitudinal axis 110 in a root section 125 then extending in a radial fashion 130 to the outer periphery portion 105, the outer periphery portion 105 further includes a plurality of asymmetrical gear teeth 270, 375 extending radially outward, see in particular, FIGS. 1 to 10 and 16 to 30.

Further included in the article bender apparatus 50 is the receptacle housing 356 that includes a radially slotted 367 annular cavity having the slide surface 357 and the radial internal diameter 358 that both provide a partially nested axial and outer periphery slidable contact for the plurality of asymmetrical gear teeth 375 extending radially outward on the outer periphery portion 105 of the disc 90, a radial slot 367 is disposed therethrough the annular cavity, thus the receptacle housing 356 operationally allowing for free disc rotation 385, 390 about the longitudinal axis 110.

The receptacle housing 356 also includes a top surface 359 approximately in the form of a ring that is parallel to the slide surface 357 and is positioned radially outward of the radial internal diameter 358, the receptacle housing 356 additionally includes a recessed cavity 386 with the floor 387 wherein the recessed cavity 386 floor 387 is in plane with the slide surface 357. Further the recessed cavity 386 extends radially outward from the slide surface 357 for circumferentially a portion of the plurality of asymmetrical gear teeth 375 on the disc 90, further the top surface 359 extends outward from the recessed cavity 386 as the top surface 359 is continuously outward of the plurality of asymmetrical gear teeth 375 on the disc 90 and the recessed cavity 386, see FIGS. 1 to 21.

Further included in the article bender apparatus 50 is the pawl element 360 that is substantially planar including the first side 364 and an opposing second side 365 that are both planar in shape, further the pawl 360 includes a primary boundary margin 403 and a secondary 404 boundary margin that are both disposed as between the first 364 and second 365 sides of the pawl 360. The pawl 360 also includes a plurality of asymmetrical gear teeth 361 disposed opposite of the primary 403 and secondary 404 boundary margins, the pawl 360 plurality of asymmetrical gear teeth 361 removably mate, through the pawl 360 second side 365 sliding against the recessed cavity 386 floor 387, with the disc 90 outer periphery portion 105 plurality of asymmetrical gear teeth 375 extending radially outward, resulting in the pawl 360 being slidably disposed within the recessed cavity 386 with the pawl 360 second side 365 being in the slidable contact with the recessed cavity 386 floor 387.

Wherein the receptacle 356, the disc 90 outer periphery portion 105 plurality of asymmetrical gear teeth 375 extending radially outward, and the pawl 360 plurality of asymmetrical gear teeth 361 that removably mate with the disc 90 outer periphery portion 105 plurality of asymmetrical gear teeth 375, form a ratchet 355 that operationally facilitates clockwise rotation 385 of the disc 90 and receptacle 356 in unison about the longitudinal axis 110 and facilitates counter clockwise rotation 351 of the receptacle 356 about the longitudinal axis 110 while the disc 90 is either static rotationally or the receptacle 356 is static rotationally and the disc 90 can be manually rotated clockwise 385 about the longitudinal axis 110, see FIGS. 1 to 21.

Further included in the article bender apparatus 50 is a shoe 135 that is planar 140 in shape having a primary planar face portion 145 and an opposing secondary planar face portion 150, the shoe 135 has a lengthwise axis 155 and a

perpendicularly positioned 165 shortwise axis 160, the shoe 135 has a first end portion 170 and an opposing second end portion 175 with the lengthwise axis 155 spanning therebetween. Further, the shoe 135 has an axial axis 180 that is perpendicular 185 to both the lengthwise 155 and shortwise 160 axes, wherein the axial axis 180 spans between the primary 145 and secondary 150 planar face portions also the axial axis 180 is positioned parallel 190 to the disc 90 longitudinal axis 110. With the primary planar face portion 145 having a slidable/pivotal engagement 195 to the disc 90 second face portion 100, about the axial axis 180, the shoe 135 first end portion 170 terminates in a first channel 200 that is positioned longwise to be parallel 235 to the shortwise axis 160, see in particular, FIGS. 4 to 15 and 22 to 30.

Additionally included in the article bender apparatus 50 is a means 240 for a selectable pivotal lock with pivotal movement 245 between the disc 90 and the shoe 135, the pivotal lock is about the axial axis 180, wherein the shoe 135 is an open operational state 250 when the slot 120 is fully open and the shoe 135 is in a closed locked operational state 255 when the shoe 135 partially covers the slot 120 leaving the slot root section 125 open, see FIGS. 1 to 15 and 22 to 30.

Also included in the article bender apparatus 50 is a means 270 for imparting a clockwise rotational movement 385 to the receptacle 356, wherein the rotational movement 275, 385 is about the longitudinal axis 110, wherein operationally the disc 90 is inserted 280 onto the first line free end portion 55 with the first line long axis 60 therethrough the disc 90 slot 120 from the outer periphery portion 105 to the root section 125 resulting in the longitudinal axis 110 and the first line long axis 60 being substantially co-incident 285 to one another, next the shoe 135 is manually moved 290 through the pivotal movement 245 from the open state 250 to the closed locked state 255 resulting in the first line free end portion 55 being secured within the root section 125. Continuing simultaneously during the shoe 135 being manually moved 295 the first channel 200 is aligned to partially encompass the second line free end portion 65, resulting in both the first line free end portion 55 being secured within the root section 125 and the shoe 135 first channel 200 to partially encompass the second line free end portion 65, next the imparting of rotational movement 275, 385 to the disc 90 is initiated to result in the selected helical wrap 85 of the second line free end portion 65 around the first line free end portion 55 being about the first line long axis 60, see FIGS. 22 to 30.

As an option for the article bender apparatus 50, wherein the shoe 135 further comprises a first ridge 205 that is disposed between the first channel 200 and the adjacent primary planar face portion 145 wherein the first ridge 205 forms an acute angle 210 between the shortwise axis 160 and the first ridge 205 to operationally add clearance 220 for an adjacent immediately prior helical wrap 85, see FIGS. 4 to 15 and 22 to 30.

Another option for the article bender apparatus 50, wherein the shoe 135 first ridge 205 in conjunction with the first channel 200 are positioned along the shoe 135 axial axis 180 to be closer 225 to the secondary planar face portion 150 than to the primary planar face portion 145 to operationally create clearance 230 for the adjacent second line free end portion 65 to the shoe 135 as the disc 90 rotates 275, 385 with the rotational movement 275 about the longitudinal axis 110 and the first line 55 long axis 60 in creating the helical wrap 85, see FIGS. 4 to 15 and 22 to 30.

Another further option for the article bender apparatus 50, the pawl 360 primary boundary margin 403 is a constant arc

radius defined by a third radius 394 originating at the longitudinal axis 110 and the pawl 360 secondary boundary margin 404 is a decreasing arc radius defined by a decreasing fourth radius 395 originating at the longitudinal axis 110. The recessed cavity 386 extends radially outward from the slide surface 357 that forms a slide surface 357 consistent termination margin 388 at a first radius 392 originating at the longitudinal axis 110 to form a consistent operational gap width 396 between the primary boundary margin 403 and the slide surface consistent termination margin 388.

The consistent operational gap width 396 is at least equal to a tooth height 398 of the asymmetrical gear teeth 375 on the disc 90 with the pawl 360 plurality of asymmetrical gear teeth 361 removably mated with the disc 90 outer periphery portion 105 plurality of asymmetrical gear teeth 375, further the recessed cavity 386 extends radially outward from the slide surface 357 that forms a slide surface converging termination margin 389 at a second decreasing radius 393 originating at the longitudinal axis 110 to form a converging operational gap width 397 between the secondary boundary margin 404 and the slide surface 357 converging termination margin 389.

Wherein the consistent 388 and converging 389 termination margins combine to be circumferentially a portion of the plurality of asymmetrical gear teeth 375 on the disc 90, further the top surface 359 extends outward from the recessed cavity 386 consistent 388 and converging 389 termination margins as the top surface 359 is continuously outward of the plurality of asymmetrical gear teeth 375 on the disc 90 and the recessed cavity 386, see FIGS. 16 to 21.

Alternatively, for the article bender apparatus 50, it can further comprise a cover ring 371 that is partially attached to the receptacle 356 top surface 359 wherein the cover ring 371 also includes an inward internal diameter surface 366 that is positioned co-axial and coincident diameter wise to the radial internal diameter surface 358 to encapsulate on three sides the plurality of asymmetrical gear teeth 375 extending radially outward from the outer periphery portion 105 of the disc 90. Further the cover ring 371 encapsulates the recessed cavity 386 to operationally substantially limit the pawl 360 to slidable movement 401, 402 within the recessed cavity 386 to the pawl 360 plurality of asymmetrical gear teeth 361 to removably mate with the disc 90 outer periphery portion 105 plurality of asymmetrical gear teeth 375, wherein ultimately operationally allowing for free disc 90 clockwise rotation 385 about the longitudinal axis 110 within the receptacle 356 and the cover ring 371, see FIGS. 16 to 21.

Further, alternatively for the article bender apparatus 50, it can further comprise a means 391 for biasing the pawl 360 toward the converging operational gap width 397 within the recessed cavity 386, operationally the means 391 for biasing the pawl 360 results in defaulting with movement 401 the pawl 360 into a first operational state 400 to engage the plurality of asymmetrical gear teeth 361, 375 as between the pawl 360 and the disc 90 thus resulting in the ratchet 355 rotationally locking the receptacle 356 and the disc 90 rotationally about the longitudinal axis 110 in a clockwise direction rotation 385. If the receptacle 356 is rotated about the longitudinal axis 110 in a counterclockwise direction 350 rotation with the disc 90 rotationally locked, the disc 90 plurality of asymmetrical gear teeth 375 will drive the pawl 360 against the means 391 for biasing the pawl 360, sliding 402 the pawl 360 away from the converging operational gap width 397 toward the consistent operational gap width 396 to facilitate the plurality of asymmetrical gear teeth 361, 375 as between the pawl 360 and the disc 90 to disengage 402

thus resulting in the pawl 360 being in a second operational state 405, see FIGS. 16 to 21.

Further, alternatively for the article bender apparatus 50, the means 391 for biasing the pawl 360 is constructed of a spring, see FIGS. 16 to 18.

Continuing, alternatively for the article bender apparatus 50, wherein the means 240 for the selectable pivotal lock is preferably constructed of a cam lock clamp 420 with a quick release handle with the pivot bolt 425, wherein when the cam lock clamp 420 with a quick release handle is in a locked or closed operational state 421 when the pivot bolt 425 is pulled axially tight as between the disc 90 and the shoe 135 along the axial axis 180 of the shoe 135. Wherein the pivot bolt 425 is disposed therethrough the disc 90 and the shoe 135 in a shoe aperture 181, the locked or closed operational state 421 of the cam lock clamp 420 with a quick release handle results in the cam lock clamp 420 with a quick release handle. Wherein the handle 420 is positioned to be adjacent 421 to the disc 90 first face portion 95, wherein when the cam lock clamp 420 with a quick release handle is in the open or released operational state 422 the pivot bolt 425 is released to be loose axially allowing the disc 90 and the shoe 135 to separate with the handle 420 being positioned perpendicular to the disc 90 first face portion 95, see FIGS. 1 to 12 and 22 to 30.

Another alternative for the article bender apparatus 50, wherein the means 270 for imparting clockwise rotational movement to the receptacle 356 is constructed of a handle 345 extension that is positioned radially outward from the receptacle housing 356, wherein operationally the handle 345 extension partially rotates the receptacle housing 356 about the longitudinal axis 110 to operate the ratchet 355 to rotate the disc 90 in a clockwise rotational direction 385, see FIGS. 1 to 4.

A further option for the article bender apparatus 50, wherein the shoe can further include the retainer bar 450 that shares the pivot bolt 425 with the shoe 135 along and about the axial axis 180, wherein the retainer bar 450 is disposed between the shoe 135 and the disc 90 second face portion 100 at a displaced pivotal angle to the shoe 135 lengthwise axis 155. Wherein operationally the retainer bar 450 contacts the first line free end portion 55 within the root section 125 of the slot 120 when the shoe 135 is in a closed locked operational state 255, 421, further included is a stop pin 455 disposed in the disc 90 second face portion 100 that protrudes in a perpendicular manner, wherein the stop pin 455 stops a pivotal movement 245 of the shoe 135 and retainer bar 450 about the axial axis 180 in the shoe 135 open operational state 250, 422 to help pivotally 245, 260, 290, position the first channel 200 to the second line free end portion 65, to start the selected pivotal wrap 85, see FIGS. 4, 5, 8, 9 to 14, and 22 to 30.

Another option for the article bender apparatus 50, can further comprise the flat spring 430 with an arcuate shape 55 forming an arcuate band that is mounted in a cantilever manner on a pivot rod 435 that is disposed therethrough a flat spring aperture 445 disposed in the disc 90 going from the second face portion 100 to the first face portion 95, wherein as the flat spring 430 is on the second face portion 60 the pivot rod 435 is attached to a flat spring handle 440 that manually facilitates flat spring 430 pivotal movement 460. Wherein operationally, the flat spring 430 acts to help hold the second line free end portion 65 into the shoe 135 first channel 200 for the shoe 135 to start the selected helical wrap 85 of the second line free end portion 65 being helically wrapped 85 about the first line 55, see FIGS. 5 to 10 and 22-30.

A further option for the article bender apparatus 50, is wherein the flat spring handle 440 can further comprise the spring ball protrusion 465 that is disposed to face the disc 90 first face portion 95, wherein the disc 90 first face portion 95 can also further include the receiving depression 470 that is positioned, sized, and configured to receive the spring ball protrusion 465 to operationally lock the flat spring handle 440 at a particular flat spring 430 pivotal movement 460 position to best operationally hold the second line free end portion 65 into the shoe 135 first channel 200 for the shoe 135 to start the selected helical wrap 85 of the second line free end portion 65 being helically wrapped 85 about the first line 55, see FIGS. 5 to 10 and 22 to 30.

Also, optionally for the article bender apparatus 50, wherein the disc 90 can further comprise the finger hole aperture 415 disposed therethrough the disc 90 from the first face portion 95 to the second face portion 100 to operationally facilitate manual rotational movement 385, 390 of the disc 90 within the receptacle 356 about the longitudinal axis 110 to help a user rotationally align the disc 90 slot 120 to the receptacle slot 367 or the shoe 135 first channel 200 with the first 55 or second 65 lines to initiate use of the article bender apparatus 50, see FIGS. 1 to 4 and 22 to 30.

Method of Use

Broadly in referring to FIGS. 1 to 30, a method of using the article bender apparatus 50 is disclosed that assists in joining two separate malleable article line free ends that are defined as a first line free end portion 55 with a first line long axis 60 and a second line free end portion 65 with a second line long axis 70 when the first 60 and second 70 line long axes are positioned substantially perpendicular 75 to one another, the article bender apparatus 50 assists in joining 80 the first 55 and second line 65 free end portions in a selected helical wrap 85, see FIGS. 22 to 30, the method of using the article bender apparatus 50 comprises the steps of;

Providing the article bender apparatus 50 as previously described.

Moving the flat spring 430 via the flat spring handle 440 to pivot away 460 from the disc 30 slot 120, see FIGS. 5 to 10 and 22 to 30.

Moving the cam lock clamp 420 with the quick release handle into the open or released operational state 422 such that the pivot bolt 425 is released to be loose axially allowing the disc 90 and the shoe 135 and retainer bar 450 to separate from the disc 90 second face portion 100 with the cam lock clamp 420 quick release handle being positioned perpendicular to the disc 90 first face portion 95, see FIGS. 4, 5, 22, and 30.

Aligning manually the disc 90 rotationally 385 about the longitudinal axis 110 utilizing the finger hole 415 to align the disc 90 slot 120 and the receptacle 356 slot 367 with the first line free end portion 55, see FIGS. 1, 3, 4 and 22-30.

Moving the disc 90 slot 120 to receive the first line free end portion 55 into the root section 125 of the slot 120, thus the disc 90 is inserted 280 onto the first line free end portion 55 with the first line long axis 60 therethrough the disc 90 slot 120 from the disc 90 outer periphery portion 105 to the root section 125 resulting in the longitudinal axis 110 and the first line 55 long axis 60 being substantially co-incident 285 to one another, see FIGS. 22 to 30.

Moving 295, 326 the shoe 135 and the retainer bar 450 manually in a pivotal manner 245, 260, 290 to position the retainer bar 450 to wherein the retainer bar 450 contacts the first line free end portion 55 within the root section 125 of the slot 120, manually in a pivotal manner 245, 260, 290 to

position the retainer bar 450 to wherein the retainer bar 450 contacts the first line free end portion 55 within the root section 125 of the slot 120 to pivotally position 245, 260, 290 the first channel 200 relative to the second line free end portion 65, see FIGS. 22-30.

Moving the cam lock clamp 420 with the quick release handle into the locked or closed operational state 421 wherein the pivot bolt 425 is pulled axially tight as between the disc 90 and the retainer bar 450 and the shoe 135 along the axial axis 180 of the shoe 135 and the retainer bar 450, wherein the quick release handle 420 is positioned to be adjacent to the disc 90 first face portion 95, see FIGS. 1 to 10 and 22 to 30.

Aligning the shoe 135 first channel 200 to partially 15 encompass the second line free end portion 65, resulting in both the first line free end portion 55 being secured within the root section 125 and the shoe 135 first channel 200 to partially encompass the second line free end portion 65, see FIGS. 22 to 30.

Moving the flat spring 430 via the flat spring 430 handle 440 to pivot 460 towards the second line free end portion 65 that is partially encompassed within the shoe 135 first channel 200 in order to help retain the second line free end portion 65 within the shoe 135 first channel 200 via utilizing 25 the flat spring 430 handle 440 spring ball protrusion 465 that is manually disposed into the receiving depression 470 in the disc 90 first face 95 to operationally lock the flat spring 430 handle 440 at the particular flat spring 430 pivotal movement position 460 to help retain the second line free end portion 65 within the shoe 135 first channel 200, see FIGS. 5 to 10 and 22 to 30.

Imparting of clockwise rotational movement 350 about the longitudinal axis 110 to the receptacle 356 and thus the disc 90 rotation 385 via the ratchet 355 that is initiated to 35 result in the selected helical wrap 85 of the second line free end portion 65 around the first line free end portion 55 being about the first line long axis 60, see FIGS. 22 to 30.

Continuing the clockwise receptacle 356 rotation movement 350 in the previous imparting step by having ratcheting movement 350 until the selected number of helical wraps 85 of the second line free end portion 65 around the first line free end portion 55 is completed, see FIGS. 22 to 30.

Moving the cam lock clamp 420 with the quick release handle into the open or released operational state 422 such that the pivot bolt 425 is released to be loose axially allowing the disc 90 and the shoe 135 and retainer bar 450 to separate from the disc 90 second face portion 100 with the cam lock clamp 420 quick release handle being positioned perpendicular to the disc 90 first face portion 95, see FIGS. 50 to 22 to 30.

Removing the shoe 135 channel 200 from the second line free end portion 65 and removing the disc 90 slot 120 from the first line free end portion 55, see FIG. 30.

CONCLUSION

Accordingly, the present invention of an Article Bender Apparatus has been described with some degree of particularity directed to the embodiments of the present invention. It should be appreciated, though; that the present invention is defined by the following claims construed in light of the prior art so modifications or changes may be made to the exemplary embodiments of the present invention without departing from the inventive concepts contained therein.

The invention claimed is:

1. An article bender apparatus that assists in joining two separate malleable article line free ends that are defined as

a first line free end portion with a first line long axis and a second line free end portion with a second line long axis when said first and second line long axes are positioned substantially perpendicular to one another, said article bender apparatus assists in joining the first and second line free end portions in a selected helical wrap with the second line free end portion being helically wrapped about the first line, comprising:

(a) a disc having a first face portion and an opposing second face portion, further said disc having an outer periphery portion that is about a longitudinal axis that is centered in said disc, wherein said longitudinal axis is positioned perpendicular to both said first and second face portions, in addition said disc has a slot disposed therethrough from said first face portion to said second face portion, wherein said slot originates from said longitudinal axis in a root section then extending in a radial fashion to said outer periphery portion, said outer periphery portion further includes a plurality of asymmetrical gear teeth extending radially outward;

(b) a receptacle housing that includes a radially slotted annular cavity having a slide surface and a radial internal diameter that both provide a partially nested axial and outer periphery slidable contact for said plurality of asymmetrical gear teeth extending radially outward on said outer periphery portion of said disc, a radial slot is disposed therethrough said annular cavity, thus said receptacle housing operationally allowing for free disc rotation about said longitudinal axis, said receptacle housing also includes a top surface approximately in the form of a ring that is parallel to said slide surface and is positioned radially outward of said radial internal diameter, said receptacle additionally includes a recessed cavity with a floor wherein said recessed cavity floor is in plane with said slide surface, further said recessed cavity extends radially outward from said slide surface for circumferentially a portion of said plurality of asymmetrical gear teeth on said disc, further said top surface extends outward from said recessed cavity as said top surface is continuously outward of said plurality of asymmetrical gear teeth on said disc and said recessed cavity;

(c) a pawl element that is substantially planar including a first side and an opposing second side that are both planar in shape, further said pawl includes a primary boundary margin and a secondary boundary margin that are both disposed as between said first and second sides of said pawl, said pawl also includes a plurality of asymmetrical gear teeth disposed opposite of said primary and secondary boundary margins, said pawl plurality of asymmetrical gear teeth removably mate, through said pawl second side sliding against said recessed cavity floor, with said disc outer periphery portion plurality of asymmetrical gear teeth extending radially outward, resulting in said pawl being slidably disposed within said recessed cavity with said pawl second side being in said slidable contact with said recessed cavity floor, wherein said receptacle, said disc outer periphery portion plurality of asymmetrical gear teeth extending radially outward, and said pawl plurality of asymmetrical gear teeth that removably mate with said disc outer periphery portion plurality of asymmetrical gear teeth, form a ratchet that operationally facilitates clockwise rotation of said disc and receptacle in unison about said longitudinal axis and facilitates counter clockwise rotation of said receptacle about said longitudinal axis while said disc is either

static rotationally or said receptacle is static rotationally and said disc can be manually rotated clockwise about said longitudinal axis;

(d) a shoe that is planar in shape having a primary planar face portion and an opposing secondary planar face portion, said shoe has a lengthwise axis and a perpendicularly positioned shortwise axis, said shoe has a first end portion and an opposing second end portion with said lengthwise axis spanning therebetween, further said shoe has an axial axis that is perpendicular to both said lengthwise and shortwise axes, wherein said axial axis spans between said primary and secondary planar face portions also said axial axis is positioned parallel to said disc longitudinal axis with said primary planar face portion having a slidable/pivotal engagement to said disc second face portion about said axial axis, said shoe first end portion terminates in a first channel that is positioned longwise to be parallel to said shortwise axis;

(e) a means for a selectable pivotal lock with pivotal movement between said disc and said shoe about said axial axis, wherein said shoe is in an open operational state when said slot is fully open and said shoe is in a closed locked operational state when said shoe partially covers said slot leaving said slot root section open; and

(f) a means for imparting a clockwise rotational movement to said receptacle, wherein said clockwise rotational movement is about said longitudinal axis, wherein operationally said disc is inserted onto the first line free end portion with the first line long axis therethrough said disc slot from said outer periphery portion to said root section resulting in said longitudinal axis and the first line long axis being substantially co-incident to one another, next said shoe is manually moved through said pivotal movement from said open state to said closed locked state resulting in the first line free end portion being secured within said root section, simultaneously during said shoe being manually moved said first channel is aligned to partially encompass the second line free end portion, resulting in both the first line free end portion being secured within said root section and said shoe first channel to partially encompass the second line free end portion, next said imparting of clockwise rotational movement to said disc is initiated to result in the selected helical wrap of the second line free end portion around the first line free end portion being about the first line long axis.

2. An article bender apparatus according to claim 1 wherein said shoe further comprises a first ridge that is disposed between said first channel and an adjacent said secondary planar face portion wherein said first ridge forms an acute angle between said shortwise axis and said first ridge to operationally add clearance for an adjacent immediately prior helical wrap.

3. An article bender apparatus according to claim 2 wherein said shoe first ridge in conjunction with said first channel are positioned along said shoe axial axis to be closer to said secondary planar face portion than to said primary planar face portion to operationally create clearance for the adjacent second line free end portion to said shoe as said disc rotates with said rotational movement about said longitudinal axis and the first line long axis in creating the helical wrap.

4. An article bender apparatus according to claim 1 wherein said pawl primary boundary margin is a constant arc radius defined by a third radius originating at said longitudinal axis and said pawl secondary boundary margin is a

decreasing arc radius defined by a decreasing fourth radius originating at said longitudinal axis, said recessed cavity extends radially outward from said slide surface forms a slide surface consistent termination margin at a first radius originating at said longitudinal axis to form a consistent operational gap width between said primary boundary margin and said slide surface consistent termination margin, said consistent operational gap width is at least equal to a tooth height of said asymmetrical gear teeth on said disc with said pawl plurality of asymmetrical gear teeth removably mated with said disc outer periphery portion plurality of asymmetrical gear teeth, further said recessed cavity extends radially outward from said slide surface forms a slide surface converging termination margin at a second decreasing radius originating at said longitudinal axis to form a converging operational gap width between said secondary boundary margin and said slide surface converging termination margin, wherein said consistent and converging termination margins combine to be circumferentially a portion of said plurality of asymmetrical gear teeth on said disc, further said top surface extends outward from said recessed cavity consistent and converging termination margins as said top surface is continuously outward of said plurality of asymmetrical gear teeth on said disc and said recessed cavity.

5. An article bender apparatus according to claim 4 further comprising a cover ring that is partially attached to said receptacle top surface wherein said cover ring also includes an inward internal diameter surface that is positioned coaxial and coincident diameter wise to said radial internal diameter surface to encapsulate on three sides said plurality of asymmetrical gear teeth extending radially outward from said outer periphery portion of said disc, further said cover ring encapsulates said recessed cavity to operationally substantially limit said pawl to slidable movement within said recessed cavity to said pawl plurality of asymmetrical gear teeth to removably mate with said disc outer periphery portion plurality of asymmetrical gear teeth, wherein ultimately operationally allowing for free disc clockwise rotation about said longitudinal axis within said receptacle and said cover ring.

6. An article bender apparatus according to claim 5 further comprising a means for biasing said pawl toward said converging operational gap width within said recessed cavity, operationally said means for biasing said pawl results in defaulting said pawl into a first operational state to engage said plurality of asymmetrical gear teeth as between said pawl and said disc thus resulting in said ratchet rotationally locking said receptacle and said disc rotationally about said longitudinal axis in a clockwise direction rotation, if said receptacle is rotated about said longitudinal axis in a counterclockwise direction rotation with said disc rotationally locked, said disc plurality of asymmetrical gear teeth will drive said pawl against said means for biasing said pawl, sliding said pawl away from said converging operational gap width toward said consistent operational gap width to facilitate said plurality of asymmetrical gear teeth as between said pawl and said disc to disengage thus resulting in said pawl being in a second operational state.

7. An article bender apparatus according to claim 6 wherein said means for biasing said pawl is constructed of a spring.

8. An article bender apparatus according to claim 1 wherein said means for a selectable pivotal lock is constructed of a cam lock clamp with a quick release handle with a pivot bolt, wherein when said cam lock clamp with a quick release handle is in a locked or closed operational

5 state said pivot bolt is pulled axially tight as between said disc and said shoe along said axial axis of said shoe, wherein said pivot bolt is disposed therethrough said disc and said shoe in a shoe aperture, said locked or closed operational state of said cam lock clamp with a quick release handle results in said cam lock clamp with a quick release handle, wherein said handle is positioned to be adjacent to said disc first face portion, wherein when said cam lock clamp with a quick release handle is in an open or released operational state 10 said pivot bolt is released to be loose axially allowing said disc and said shoe to separate with said handle being positioned perpendicular to said disc first face portion.

15 9. An article bender apparatus according to claim 1 wherein said means for imparting clockwise rotational movement to said receptacle is constructed of a handle extension that is positioned radially outward from said receptacle housing, wherein operationally said handle extension partially rotates said receptacle housing about said longitudinal axis to operate said ratchet to rotate said disc in a clockwise rotational direction.

20 10. An article bender apparatus according to claim 8 wherein said shoe further includes a retainer bar that shares said pivot bolt with said shoe along and about said axial axis, 25 wherein said retainer bar is disposed between said shoe and said disc second face portion at a displaced pivotal angle to said shoe lengthwise axis, wherein operationally said retainer bar contacts the first line free end portion adjacent to said root section of said slot when said shoe is in a closed 30 locked operational state, further included is a stop pin disposed in said disc second face portion that protrudes in a perpendicular manner, wherein said stop pin stops a pivotal movement of said shoe and retainer bar about said axial axis in said shoe closed operational state to help pivotally position said first channel of said shoe in relation to the second line free end portion to help start the selected helical wrap.

35 11. An article bender apparatus according to claim 10 further comprising a flat spring with an arcuate shape forming an arcuate band that is mounted in a cantilever manner on a pivot rod that is disposed therethrough a flat spring aperture disposed in said disc going from said second face portion to said first face portion, wherein as said flat spring is on said second face portion said pivot rod is 40 attached to a flat spring handle that manually facilitates flat spring pivotal movement, wherein operationally said flat spring acts to help hold the second line free end portion into said shoe first channel for the shoe to start the selected helical wrap of the second line free end portion being helically wrapped about the first line.

45 12. An article bender apparatus according to claim 11 wherein said flat spring handle further comprises a spring ball protrusion that is disposed to face said disc first face portion, wherein said disc first face portion further includes 50 a receiving depression that is positioned, sized, and configured to receive said spring ball protrusion to operationally lock said flat spring handle at a particular flat spring pivotal movement position to best operationally hold the second line free end portion into said shoe first channel for the shoe to start the selected helical wrap of the second line free end portion being helically wrapped about the first line.

55 13. An article bender apparatus according to claim 1 wherein said disc further comprises a finger hole aperture disposed therethrough said disc from said first face portion to said second face portion to operationally facilitate manual rotational movement of said disc within said receptacle about said longitudinal axis to help a user rotationally align

said disc slot with said receptacle slot or said shoe first channel with the first or second lines to initiate use of said article bender apparatus.

14. A method of using an article bender apparatus that assists in joining two separate malleable article line free ends that are defined as a first line free end portion with a first line long axis and a second line free end portion with a second line long axis when said first and second line long axes are positioned substantially perpendicular to one another, said article bender apparatus assists in joining the first and second line free end portions in a selected helical wrap with the second line free end portion being helically wrapped about the first line, comprising:

- (a) providing an article bender apparatus that includes a disc having a first face portion and an opposing second face portion, further said disc having an outer periphery portion that is about a longitudinal axis that is centered in said disc, wherein said longitudinal axis is positioned perpendicular to both said first and second face portions, in addition said disc has a slot disposed therethrough from said first face portion to said second face portion, wherein said slot originates from said longitudinal axis in a root section then extending in a radial fashion to said outer periphery portion, said outer periphery portion further includes a plurality of asymmetrical gear teeth extending radially outward, further a receptacle housing that includes a radially slotted annular cavity having a slide surface and a radial internal diameter that both provide a partially nested axial and outer periphery slidable contact for said plurality of asymmetrical gear teeth extending radially outward on said outer periphery portion of said disc, a radial slot is disposed therethrough said annular cavity, thus said receptacle housing operationally allowing for free disc rotation about said longitudinal axis, said receptacle housing also includes a top surface approximately in the form of a ring that is parallel to said slide surface and is positioned radially outward of said radial internal diameter, said receptacle additionally includes a recessed cavity with a floor wherein said recessed cavity floor is in plane with said slide surface, further said recessed cavity extends radially outward from said slide surface for circumferentially a portion of said plurality of asymmetrical gear teeth on said disc, further said top surface extends outward from said recessed cavity as said top surface is continuously outward of said plurality of asymmetrical gear teeth on said disc and said recessed cavity, also including a pawl element that is substantially planar including a first side and an opposing second side that are both planar in shape, further said pawl includes a primary boundary margin and a secondary boundary margin that are both disposed as between said first and second sides of said pawl, said pawl also includes a plurality of asymmetrical gear teeth disposed opposite of said primary and secondary boundary margins, said pawl plurality of asymmetrical gear teeth removably mate, through said pawl second side sliding against said recessed cavity floor, with said disc outer periphery portion plurality of asymmetrical gear teeth extending radially outward, resulting in said pawl being slidably disposed within said recessed cavity with said pawl second side being in said slidable contact with said recessed cavity floor, wherein said receptacle, said disc outer periphery portion plurality of asymmetrical gear teeth extending radially outward, and said pawl plurality of asymmetrical gear teeth that removably mate with said disc outer

periphery portion plurality of asymmetrical gear teeth, form a ratchet that operationally facilitates clockwise rotation of said disc and receptacle in unison about said longitudinal axis and facilitates counter clockwise rotation of said receptacle about said longitudinal axis while said disc is either static rotationally or said receptacle is static rotationally and said disc can be manually rotated clockwise about said longitudinal axis, in addition a shoe that is planar in shape having a primary planar face portion and an opposing secondary planar face portion, said shoe has a lengthwise axis and a perpendicularly positioned shortwise axis, said shoe has a first end portion and an opposing second end portion with said lengthwise axis spanning therebetween, further said shoe has an axial axis that is perpendicular to both said lengthwise and shortwise axes, wherein said axial axis spans between said primary and secondary planar face portions also said axial axis is positioned parallel to said disc longitudinal axis with said primary planar face portion having a slidable/pivotal engagement to said disc second face portion about said axial axis, said shoe first end portion terminates in a first channel that is positioned longwise to be parallel to said shortwise axis, plus a means for a selectable pivotal lock with pivotal movement between said disc and said shoe about said axial axis, wherein said shoe is in an open operational state when said slot is fully open and said shoe is in a closed locked operational state when said shoe partially covers said slot leaving said slot root section open, wherein said means for a selectable pivotal lock is constructed of a cam lock clamp with a quick release handle with a pivot bolt, wherein when said cam lock clamp with a quick release handle is in a locked or closed operational state said pivot bolt is pulled axially tight as between said disc and said shoe along said axial axis of said shoe, wherein said pivot bolt is disposed therethrough said disc and said shoe in a shoe aperture, said locked or closed operational state of said cam lock clamp with a quick release handle results in said cam lock clamp with a quick release handle, wherein said handle is positioned to be adjacent to said disc first face portion, wherein when said cam lock clamp with a quick release handle is in an open or released operational state said pivot bolt is released to be loose axially allowing said disc and said shoe to separate with said handle being positioned perpendicular to said to said disc first face portion, in addition a means for imparting a clockwise rotational movement to said receptacle, wherein said clockwise rotational movement is about said longitudinal axis, wherein said means for imparting clockwise rotational movement to said receptacle is constructed of a handle extension that is positioned radially outward from said receptacle housing, wherein operationally said handle extension partially rotates said receptacle housing about said longitudinal axis to operate said ratchet to rotate said disc in a clockwise rotational direction, further on said ratchet included is pawl detail wherein said pawl primary boundary margin is a constant arc radius defined by a third radius originating at said longitudinal axis and said pawl secondary boundary margin is a decreasing arc radius defined by a decreasing fourth radius originating at said longitudinal axis, said recessed cavity extends radially outward from said slide surface forms a slide surface consistent termination margin at a first radius originating at said longitudinal axis to form a consistent operational gap

width between said primary boundary margin and said slide surface consistent termination margin, said consistent operational gap width is at least equal to a tooth height of said asymmetrical gear teeth on said disc with said pawl plurality of asymmetrical gear teeth removably mated with said disc outer periphery portion plurality of asymmetrical gear teeth, further said recessed cavity extends radially outward from said slide surface forms a slide surface converging termination margin at a second decreasing radius originating at said longitudinal axis to form a converging operational gap width between said secondary boundary margin and said slide surface converging termination margin, wherein said consistent and converging termination margins combine to be circumferentially a portion of said plurality of asymmetrical gear teeth on said disc, further said top surface extends outward from said recessed cavity consistent and converging termination margins as said top surface is continuously outward of said plurality of asymmetrical gear teeth on said disc and said recessed cavity, also said pawl further comprising a means for biasing said pawl toward said converging operational gap width within said recessed cavity, operationally said means for biasing said pawl results in defaulting said pawl into a first operational state to engage said plurality of asymmetrical gear teeth as between said pawl and said disc thus resulting in said ratchet rotationally locking said receptacle and said disc rotationally about said longitudinal axis in a clockwise direction rotation, if said receptacle is rotated about said longitudinal axis in a counterclockwise direction rotation with said disc rotationally locked, said disc plurality of asymmetrical gear teeth will drive said pawl against said means for biasing said pawl, sliding said pawl away from said converging operational gap width toward said consistent operational gap width to facilitate said plurality of asymmetrical gear teeth as between said pawl and said disc to disengage thus resulting in said pawl being in a second operational state, also included in said shoe is a retainer bar that shares said pivot bolt with said shoe along and about said axial axis, wherein said retainer bar is disposed between said shoe and said disc second face portion at a displaced pivotal angle to said shoe lengthwise axis, additionally included is a flat spring with an arcuate shape forming an arcuate band that is mounted in a cantilever manner on a pivot rod that is disposed therethrough a flat spring aperture disposed therethrough in said disc going from said second face portion to said first face portion, wherein as said flat spring is on said second face portion said pivot rod is attached to a flat spring handle that manually facilitates flat spring pivotal movement, said flat spring handle further comprises a spring ball protrusion that is disposed to face said disc first face portion, wherein said disc first face portion further includes a receiving depression that is positioned, sized, and configured to receive said spring ball protrusion to operationally lock said flat spring handle at a particular flat spring pivotal movement position to best operationally hold the second line free end portion into said shoe first channel for the shoe to start the selected helical wrap of the second line free end portion being helically wrapped about the first line, also included for said disc that can further comprise a finger hole aperture disposed therethrough said disc from said first face portion to said second face portion to operationally facilitate manual rotational

movement of said disc about said longitudinal axis within said receptacle to help a user rotationally align said disc slot or said shoe first channel with the first or second lines to initiate use of said article bender apparatus;

- (b) moving said flat spring via said flat spring handle to pivot away from said disc slot;
- (c) moving said cam lock clamp with said quick release handle into said open or released operational state such that said pivot bolt is released to be loose axially allowing said disc and said shoe and retainer bar to separate from said disc second face portion with said cam lock clamp quick release handle being positioned perpendicular to said disc first face portion;
- (d) aligning manually said disc rotationally about said longitudinal axis utilizing said finger hole to align said disc slot and said receptacle slot with the first line free end portion;
- (e) moving said disc slot to receive the first line free end portion into said root section of said slot, thus said disc is inserted onto the first line free end portion with the first line long axis therethrough said disc slot from said disc outer periphery portion to said root section resulting in said longitudinal axis and the first line long axis being substantially co-incident to one another;
- (f) moving said shoe and said retainer bar manually in a pivotal manner to position said retainer bar to wherein said retainer bar contacts the first line free end portion within said root section of said slot to pivotally position said first channel relative to the second line free end portion;
- (g) moving said cam lock clamp with said quick release handle into said locked or closed operational state wherein said pivot bolt is pulled axially tight as between said disc and said retainer bar and said shoe along said axial axis of said shoe and said retainer bar, wherein said quick release handle is positioned to be adjacent to said disc first face portion;
- (h) aligning said shoe first channel to partially encompass the second line free end portion, resulting in both the first line free end portion being secured within said root section and said shoe first channel to partially encompass the second line free end portion;
- (i) moving said flat spring via said flat spring handle to pivot towards the second line free end portion that is partially encompassed within said shoe first channel in order to help retain the second line free end portion within said shoe first channel via utilizing said flat spring handle spring ball protrusion that is manually disposed into said receiving depression in said disc first face to operationally lock said flat spring handle at said particular flat spring pivotal movement position to help retain the second line free end portion within said shoe first channel;
- (j) imparting of clockwise rotational movement about said longitudinal axis to said receptacle and thus said disc that is initiated to result in the selected helical wrap of the second line free end portion around the first line free end portion being about the first line long axis;
- (k) continuing said clockwise rotation movement in step (j) until a selected number of helical wraps of the second line free end portion around the first line free end portion is completed;
- (l) moving said cam lock clamp with said quick release handle into said open or released operational state such that said pivot bolt is released to be loose axially allowing said disc and said shoe and retainer bar to

separate from said disc second face portion with said cam lock clamp quick release handle being positioned perpendicular to said disc first face portion; and
(m) removing said shoe channel from the second line free end portion and removing said disc slot from the first 5 line free end portion.
